UNITED STATES PATENT OFFICE.

CHARLES S. SCHROEDER, OF STAMFORD, CONNECTICUT, ASSIGNOR TO THE YALE & TOWNE MANUFACTURING COMPANY, OF STAMFORD, CONNECTICUT.

ELECTRIC CONTROLLER.

Application filed October 28, 1921. Serial No. 511,162.

To all whom it may concern:

Be it known that I, CHARLES S. SCHROEDER, a citizen of the United States, and a resident of Stamford, in the county of Fairfield and 5 State of Connecticut, have invented certain new and useful Improvements in Electric Controllers; and I do hereby declare the following to be a full, clear, and exact description of the invention, such as will enable 10 others skilled in the art to which it appertains to make and use the same.

This invention relates to improvements in electric controllers and more particularly to that of the drum type,—one object of the invention being to provide a controller construction which shall be durable and compact and which will lend itself conveniently for use in the space available to receive it on a motor vehicle, particularly on an industrial truck or tractor.

A further object is to so construct the drum of the controller that either half thereof may be readily removed to facilitate inspection or repair.

25 A further object is to improve the construction and operating means of the cut-out switch.

A further object is to provide contact devices which shall be relatively large compared to the general size of the controller and so that the contact surfaces throughout the various control points shall not be interrupted by screw heads or attaching holes.

With these and other objects in view, the 35 invention consists in certain novel features of construction and combinations and arrangements of parts as hereinafter set forth and pointed out in the claims.

In the accompanying drawings; Figure 1 40 is a plan or face view of an electric controller embodying my improvements; Figure 2 is a transverse sectional view on the line 2—2 of Figure 1; Figure 3 is a view in section on the line 3—3 of Figure 1; and Figure 4 is a view on the line 4—4 of Figure 1.

The mechanism of the controller is contained within a casing 1, which may comprise two members hinged together and normally held closed by means of a suitable 50 latch.

A frame 2 is secured within the casing and is provided at its respective ends with standards 3, 4 having suitable bearings for a shaft 5 to which a controller drum 6 is se-

cured. The controller drum comprises two 55 heads 7 and 8, each rigidly secured to the shaft 5, and two segments 9, 9 connecting said heads and carrying the movable contact blocks 10, 10^a 10^b of the controller, the contact blocks on the respective segments being 60 arranged in a manner well understood in the art and adapted for cooperation with a series of contact fingers which are mounted and constructed as hereinafter explained. Each of the segments 9 which comprise the 65 body portion of the drum is composed of suitable non-conducting material curved transversely to accommodate the curvature of the contact blocks and having flanges 11 at its edges between which the larger contact 70 blocks are located. Transverse ribs 12 are formed on the intermediate portion of each segment and serve to strengthen the same and also to provide abutments for the smaller contact block 10^a, an insulating strip 13 75 being disposed between this contact block and portions of the larger contact blocks 10. The contact blocks on each segment of the drum body are secured in place by means of screws 14 passing through said segments from the inside and entering threaded sockets in 80 said blocks, so that no portions of the contact surfaces of said blocks will be interrupted by bolts or screw ends or perforations for the accommodation of such fastening 85 means. The insulating segments composing the body of the drum are removably secured to the heads 7, 8 by screws 8^a, so that either of such body segments may be readily removed to facilitate inspection or repair. 90

The end standards 3 and 4 of the supporting frame afford bearings for an operating shaft 15 and a toothed segment 16 secured to this shaft transmits motion to a gear 17 on the drum shaft for rotating the drum, and to the shaft 15 a suitable operating lever 18 is secured. In order that the drum shall be caused properly to move step by step relatively to the contact fingers, a toothed wheel or segment 19 may be made as an integral part of the drum head 7 and an arm 20 is mounted loosely on the operating shaft and provided with a roller to engage said toothed wheel, the roller on said arm being caused to forcibly engage the toothed wheel by the operation of a spring 21 connected at one end with said arm and at its other end with the frame standard 3. 100 105

Located at one side of and secured to the supporting frame, is a bar or rail 22 of non-conducting material, (preferably wood) and this bar serves as a support for a plurality of fixed brackets 23 for the contact fingers 24 of the controller. Each bracket 23 is formed with an elevated seat 23^a to receive one end of a contact finger and at one edge of each seat, a limiting shoulder 23^b for the contact finger may be provided. Each contact finger includes a comparatively broad and substantial strip 25 of suitable resilient metal, provided near one end with holes for the accommodation of screws 26 which also pass through holes in the seat portions 23^a of the brackets 23 for securing the contact fingers to said brackets. Upon each resilient finger strip 26, a plurality of thin superimposed copper strips 27 are located. These thin strips are bowed as indicated at 28 and near their rear ends adjacent to their bowed portion, elongated holes 27^a are made for the passage of the screws 26, the heads of the latter bearing upon a plate 29 located upon the superimposed copper strips. To the under face of each finger strip 25, a rounded contact blank 30, equal in width with that of the finger, is secured by means of screws 31 which pass through holes in a plate 32 on the free end portions of the superimposed copper strips, through holes in said copper strips 27 and the finger strip 26 and enter threaded sockets in the contact block 30. When the contact fingers shall have been secured in place, their resilience will be such that the contact blocks at their free ends will be pressed against the contact plates of the drum with sufficient force to insure intimate and effectual electrical contact.

A bracket 33 is secured on the bar or rail 22 near one end of the drum and may support a fuse clip 34, the other clip for the fuse being shown at 35 supported by a bracket 36 secured to the bar or rail 22, the fuse (not shown) being located in the line circuit, and in one corner of the casing, a plugging-in device 37 is located.

The fixed member 38 of a cut-out is carried by and electrically connected with the bracket 33. The movable member 39 of this cut-out is carried by an arm 40 mounted loosely upon the operating shaft 15 and said movable member is electrically connected with the first of the series of contact fingers (as indicated at 40^a) so that the cut-out will be included in series in the controlled circuit. The free end of the movable cut-out member 39 is made with a flange or lip 39^a to engage the free end of the fixed member 38 of said cut-out. To relieve the contacts of the cut-out from the wearing effect of excessive sparking, sparking contacts are provided for said cut-out and are constructed to better withstand the effects of sparking than will the main contacts. In constructing

the sparking-contacts for the cut-out, I employ a contact block 40^b of carbon which is secured to the bracket 33, and to the movable member 39 of the cut-out I secure spring fingers 41 projecting over the flange or lip 39^a of the movable member 39 and provided with comparatively large copper contact blocks 42 to cooperate with the carbon contact block 40^b—the construction and arrangement of parts being such that when the cut-out is opened, the sparking contacts will be separated just after the separation of the main contact members of the cut-out.

The cut-out is maintained closed during the normal operation of the controller, by the action of a spring 43 attached at one end to the frame standard 4 and at the other end to a lateral projection 44 on the arm or support 40 for the movable member of the cut-out. The arm or support 40 is provided on its under or rear side with a tooth 45 and the drum shaft 5 is provided with a notched arm 45^a to engage said tooth to open the cut-out when the drum is at or returned to neutral position, the construction being such that the cut-out will be opened just prior to the opening of the circuit at the drum and finger contacts of the controller and thus prevent sparking at said contacts.

A sleeve 46 is mounted loosely on the drum shaft and is provided with a cam arm 47 to cooperate with a roller 48 on the lateral projection 44 of the arm or support 40. The sleeve 46 is also provided with an L-shaped arm 50 with which a rod 49 is connected. The rod 49 is intended for connection with a brake pedal or lever (not shown) so that when said pedal or lever is operated to apply the brake, the cam arm 47 will cooperate with the roller 48 and thus move the arm or support 40 so as to open the cut-out regardless of the position of the controller drum when the brake is applied.

Having fully described my invention what I claim as new and desire to secure by Letters-Patent, is:—

1. The combination with a controller drum and contact fingers, of a cut-out comprising a fixed contact member and a movable contact member having a lip at its free end to cooperate with the free end of said fixed member, and arcing devices comprising a fixed carbon block having electrical connection with the fixed contact member of the cut-out, a spring finger secured to the movable member of the cut-out and extending over the lip thereof and a contact member secured to said spring finger and cooperable with said carbon block.

2. The combination of a controller drum, a drum shaft, contact fingers cooperable with the contacts of said drum, an operating shaft, gearing between said operating shaft and the drum shaft, an arm mounted loosely on the operating shaft, a movable cut-out

member secured to said arm, a fixed cut-out member, and an arm carried by the drum shaft and cooperable with the movable cut-out member to open the cut-out when the
5 drum approaches neutral position and to maintain said cut-out open when the drum is at neutral position.

In testimony whereof, I have signed this specification in the presence of two subscribing witnesses.

CHARLES S. SCHROEDER.
